ROCKER ARM BEARING

Robert Webster Darden, Tyler, Tex.

Application February 20, 1939, Serial No. 257,554

4 Claims. (Cl. 308—21)

This invention relates to improvements in rocker arm bearings, particularly intended for use in connection with oil well pump jacks.

The primary object of this invention is to provide a rocker arm bearing comprising complementary arc surfaces forming a fulcrum for the walking beam of a pump jack, whereby vibration will be reduced and a more direct pull force may be directed to the pump rod of the well.

10 A further object of this invention is to provide a bearing of the above mentioned character which will reduce friction between the fulcrum parts and will require a minimum amount of attention from the well operator.

15 A still further object of this invention is to provide a rocker arm bearing of the above mentioned character in which the walking beam or rocker arm is caused to shift from one side to the other of the fulcrum point, thereby increasing 20 the force of pull during the extreme movements of the walking beam.

A still further object of this invention is to provide a walking beam or rocker arm bearing of the above mentioned character whereby the 25 fulcrum bearings produce a rolling action along their curved contacting faces, considerably reducing frictional wear and eliminating costly repairs.

Other objects and advantages of the invention 30 will become apparent during the course of the following description taken with the drawings, wherein,

Figure 1 is a top elevational view of a pump jack embodying this invention, illustrating a section 35 broken away adjacent the fulcrum point of the walking beam;

Figure 2 is a side elevational view illustrating the pump jack and showing the manner in which the rocker arm and pull line fulcrums are associated therewith.

Figure 3 is a fragmentary view of the walking beam fulcrum illustrating in detail the rocking surfaces thereof;

40 Figure 4 is a vertical cross sectional view of the walking beam fulcrum taken on line 4—4 of Figure 2, looking in the direction of the arrows;

45 Figure 5 is a vertical cross sectional view taken on line 5—5 of Figure 4, looking in the direction 50 of the arrows illustrating the retaining guide member for the fulcrum rocker;

Figure 6 is a fragmentary side elevational view of the pull line fulcrum connection with the walking beam operating arm;

55 Figure 7 is a top elevational view of the con-

nection between the walking beam operator and the pull link line;

Figure 8 is a vertical cross sectional view taken on line 8—8 of Figure 7, looking in the direction of the arrows further illustrating the connection 5 between the walking beam operator and pull line, and

Figure 9 is a cross sectional view similar to Figure 8 and taken at right angles thereto.

In the drawings, wherein for the purpose of illustrating the invention and wherein like reference characters will be employed to designate like parts throughout the same, the reference character 5 will generally be employed to designate a pump jack commonly employed in well pumping operations and includes side frame base angle bars 6 which may be anchored to a concrete base 7 or other suitable support. The pump frame structure also includes a pair of vertical angular members 8 connected at the top by means of a horizontal frame member 9 riveted or welded thereto as at 10. A brace bar 11 may have its ends connected to one side of the horizontal bar 9 while the other end is connected to the opposite end of the base bar frame member 6.

The above constitutes a frame for a pump jack for supporting the walking beam 12 fulcrumed as at 13 to the top rail 9, and having on one end, a sector-shaped sheave 14 to which one end of the pump cable 15 is secured. Extending downwardly and connected to the walking beam 12 is an operating lever 16 braced by means of a bar 17 having one end connected to the walking beam 12 and the opposite end connected to the operating lever 16.

30 The pump cable 15 extends downwardly through a well casing guide 18 and may be connected to the sector-shaped sheave 14 by means of a suitable clevis so that the pump cable will follow a straight line path during its vertical reciprocation. To reinforce the sector-shaped sheave, a brace bar 20 is provided. The walking beam 12 is oscillated by means of a horizontal pull link 21 connected to a donkey engine as at 22 and fulcrumed to the walking beam operator arm 16 at 40 the opposite end.

45 The invention also includes a walking beam fulcrum comprising a segment-shaped block 23 bolted to the top rail 9 of the pump jack frame as at 24 and it is to be understood that a pair 50 of frames are provided in spaced relation so that the walking beam 12 may oscillate therebetween. Also, that there will be provided a fulcrum block 23 on each top rail 9. Each fulcrum block 23 includes a relatively straight 55

vertical wall 25 terminating in a downwardly inclined arcuately curved surface 26. A recess 27 is formed on the inner wall of each segment-shaped fulcrum block for receiving a guide member carried by the walking beam supporting rocker which will be hereinafter more fully described.

Mounted on opposite sides of the web portion of the walking beam 12 are laterally extending arms 28, the inner ends of which are provided with base plates 30 anchored in place by rivets or nuts and bolts 31. Secured to the free end of each laterally extending supporting arm are rocker bearings 32 having a bearing face 33 corresponding to the arcuately curved surface 26 of the fulcrum block 23 and adapted to rock thereon during the oscillation of the walking beam 12. The upper face of the rocker bearing is similarly shaped as at 34. Extending downwardly from each rocker bearing is an arm 35 having a curved edge 36 of a smaller circumference than the recess 27 to allow an oscillating movement of the arm 35 therein and being operative in conjunction with the bearing block 23 to prevent lateral movements of the rockers 32. Formed on the arm 35 and extending laterally therefrom is a lug 37 adapted to extend out of the pocket 27 and under a guide segment 38 which is arcuately curved and is fastened at both ends to the sector-shaped block 23, as at 39 whereby displacement of the guide arm 35 will be prevented should the walking arm be buckled when the pump cable becomes stuck or entangled.

The fulcrum connecting the pull link line to the walking beam operating arm 16 comprises a pair of spaced bearing blocks 40 connected by a base member 41 anchored to the flange of the operating arm 16 as at 42, by means of bolts or rivets. Curved bearing surfaces 43 are formed on the spaced bearing blocks 40. Formed on the inner wall of the spaced bearing blocks 40 are fulcrum pockets 44 adapted to receive fulcrum extensions 45 formed on the complementary bearing rockers 46.

Each complementary bearing rocker 46 is provided with a curved bearing surface 47 adapted to rock on the curved bearing surface 43 of the bearing blocks 40, and said bearing rockers are held in spaced relation by means of a connecting web 48. If desired, bearing faces 49 may be secured to the fulcrum arms 45 and in order to hold the bearing arms in place, a bolt 50 may extend through an angular slot 51 formed therein and through the spaced bearing blocks 40, as at 52. A nut 53 is threaded on one end of the bolt 50 thereby preventing displacement thereof.

It will be noted that the pull links 21 are each provided with a fan-shaped end 54 for connection with the bearing rocker 46 and said connection includes oppositely extending connecting pins 55 passing through suitable openings in the fan-shaped ends 54 held against displacement by cotter pins or keys 56. Anchoring pins 57 also extend through the fan-shaped ends 54 and through the bearing rocker 46 to prevent a pivotal motion 65 between the end of the pull link 21 and the rocker bearing 46.

It is to be understood that the form of the in-

vention herewith shown and described is to be taken as a preferred example of the same and that various changes in the shape, size and arrangement of parts may be made without departing from the spirit of the invention or the scope 5 of the subjoined claims.

I claim:

1. A rocker bearing comprising a stationary rocker bearing block having a curved bearing face, a movable rocker bearing member having an oppositely curved bearing face adapted to rock on the first mentioned curved bearing face, the tangent to said bearing faces at the normal points of contact being positioned at an angle approximating 45° to the vertical, operating means for 10 the movable rocker bearing member and means rigidly connected to the movable rocker bearing member and laterally freely engaged with the stationary rocker bearing block to prevent lateral displacement of the movable rocker bearing 15 member.

2. A rocker bearing comprising a stationary bearing block having a curved bearing surface, a movable rocker bearing having an oppositely curved bearing surface adapted to rock on the bearing surface of the stationary bearing block, said curved faces being the outside arcs of circles, the tangent to said arcs at the normal points of contact being positioned at an angle approximating 45° to the vertical, operating means for the 25 movable rocker bearing, and an extension formed on the inner side of the movable rocker bearing block adapted to be received in a pocket formed in the inner side of the stationary bearing block to prevent lateral displacement of the movable 30 35 rocker bearing.

3. A rocker bearing comprising a stationary bearing block having a curved bearing surface and a recess at the inner side extending inwardly from the bearing surface, a movable bearing block 40 having a cooperating curved bearing surface for rolling contact with the stationary bearing block, operating means for the movable bearing block movable in a substantially horizontal plane and an extension formed on the inner side of the 45 movable bearing block seated in said recess to prevent lateral movement of the movable bearing block.

4. A rocker bearing for pump jacks having a walking beam and a support, comprising a stationary bearing member having a curved bearing face mounted on the support, a movable bearing rocker carried by the walking beam and having a curved face adapted to roll on the stationary bearing member, said curved faces being the outside arcs of circles, the tangent to said arcs at the normal points of contact being positioned at an angle approximating 45° to the vertical, operating means for the movable bearing rocker and means carried by the movable bearing rocker and 50 cooperating with the stationary bearing member for preventing displacement of the movable bearing rocker with respect to the stationary bearing member, said means including an extension arm 55 adapted to enter a recess formed in the stationary 60 bearing member.

ROBERT WEBSTER DARDEN.
